UNITED STATES PATENT OFFICE.

ULYSSES L. COLLINS, OF ENCANTO, CALIFORNIA.

ELECTRIC CLOCK.

1,296,048.

Specification of Letters Patent.

Patented Mar. 4, 1919.

Application filed January 8, 1918. Serial No. 70,928.

To all whom it may concern:

Be it known that I, ULYSSES L. COLLINS, a citizen of the United States, residing at Encanto, San Diego county, California, have **5** invented a certain new and useful Improvement in Electric Clocks, of which the following is a full, clear, and exact description, such as will enable others skilled in the art to which it appertains to make and use the **10** same, reference being had to the accompanying drawings, forming part of this specification.

My invention relates to electric clocks of the type wherein a plurality of weights are **15** utilized as the motive power for actuating the clock mechanism and which weights are periodically elevated by means of an automatically energized electromagnet.

The principal objects of my invention are **20** to generally improve upon and simplify the existing types of electric clocks; to provide a construction which will operate positively, accurately and with minimum cost in so far as the consumption of electrical energy is **25** concerned; to combine in the operating mechanism a pair of weighted pawl carrying levers with a single ratchet wheel; to provide an improved system of leverage between the armature of the magnet and the weight **30** carrying levers, which leverage system automatically compensates for the variation of the action of the magnet upon its armature; to provide for the maintenance of bright or clean contact surfaces between the parts **35** which contact to close the circuit in which the magnet is located, and further to provide a construction which can be easily and quickly taken apart for the purpose of being cleaned, oiled or repaired.

40 With the foregoing and other objects in view, my invention consists in certain novel features of construction and arrangement of parts, hereinafter more fully described, claimed and illustrated in the accompanying **45** drawings, in which—

Figure 1 is a front elevational view of the operating mechanism of a clock of my improved construction, parts thereof being broken away and parts in section.

50 Fig. 2 is a horizontal section taken approximately on the line 2—2 of Fig. 1.

Fig. 3 is a side elevational view of the clock and its operating mechanism, parts thereof being in section.

55 Fig. 4 is a diagrammatic view illustrating the electrical circuit in which the clock is

located and also illustrating a series of secondary clocks and the electrical connections therewith.

Referring by numerals to the accompanying drawings, 10 designates the back of the clock housing, the same being preferably constructed of wood, and fixed thereto are brackets such as 11, which support the framework of the clock and which latter includes a rear plate 12 and a front plate 13, said plates being vertically disposed, parallel with each other, and framed together by suitable cross pieces. The lower one of the brackets 11 is insulated from the rear plate **60** 12 as illustrated in the diagrammatic view, Fig. 4.

The pendulum 14 swings from a suitable support 15 on the upper portion of back wall 10 and loosely connected to this pendulum is **65** the lower portion of an arm 16, the upper end thereof being fixed to a shaft 17, the same being journaled in the upper portions of plates 12 and 13 and said shaft carrying an escape lever 18. The ends of this escape **70** lever coöperate with an escapement wheel 19, the same being mounted on a shaft 20 and said escapement wheel carrying a pinion 21 with which meshes a comparatively large gear 22, and which latter is mounted on a **75** shaft 23.

Fixed to gear 22 is a small pinion 24 and meshing therewith is a large gear 25, the same being fixed on the minute hand shaft **80** 26. This shaft carries the usual minute hand 27 and is connected by the usual gearing 28 to the hour hand 29, which latter is carried by a sleeve 30 operating on said minute hand shaft.

Fixed on shaft 23 is a ratchet wheel **85** 31, preferably provided with four teeth, and loosely mounted on said shaft to the rear and immediately adjacent to said ratchet wheel are collars 32 and 33. Fixed to collar 32 is an arm 34, the outer end of which carries a weight 35 and projecting from the end of the arm which is fixed to collar 32 is a finger 36.

Pivots mounted on arm 34 is a spring-held pawl 37, the point of which is adapted to engage the teeth of ratchet wheel 31. Fixed to sleeve 33 is an arm 38 provided at its outer end with a weight 39 and projecting from the opposite end of this arm is a finger **90** 40. Pivots mounted on this finger is a **95** spring-held pawl 41, the point of which is adapted to engage the teeth of ratchet wheel

31. This ratchet wheel 31 has a comparatively wide face and the pawls are comparatively narrow and thus it is possible for the pawls to readily pass each other on the face of said ratchet wheel as the weighted arms are actuated by the armature of the magnet, as hereinafter more fully described.

The weighted arms 34 and 38 are the same length and their upward swinging movement is limited by a spring-held stop 42, which latter depends from a bracket 43 at the upper end of plate 12. The face of this stop 42 which is engaged by the weights on the ends of the arms 34 and 38 is provided 10 with a section of felt, rubber or analogous material 44, which serves as a cushion to receive the force of the impact between the weights and stop 42 and also to deaden the sound of contact between these parts.

20 Projecting from plate 12 below shaft 23 is an insulated bracket 45 and carried thereby are the coils of an electromagnet 46, the same being located directly in front of the ends of the weighted arms which are provided with the fingers 36 and 40. The armature 47 of this magnet is pivotally mounted on a bracket carried by the upper ends of the magnet coils and said armature is normally pulled upward away from the 25 cores of the magnet coils by a retractile spring 48.

Fixed to armature 47 and projecting toward shaft 23 is an arm 49, the outer end of which carries a pair of horizontally disposed pins 50 and 51, the same occupying 35 positions in the paths of travel of the fingers 36 and 40. Projecting forwardly from plate 12 is a bracket 52 and positioned thereupon is a cushion 53 of rubber, felt or analogous material, the same acting as a stop to 40 limit the upward movement of the free end of arm 49.

Referring now to diagrammatic view, Fig. 4, 54 designates a suitable battery and leading from one side thereof is a wire 55 which is connected to binding post 56 located on back wall 10 of the clock. Leading from this binding post through said back wall to the upper bracket 11 is a conductor 57. 45 Leading from the other side of battery 54 to binding post 58 is a conductor 59 and leading from said binding post 58 to the lower bracket 11, which latter is insulated from rear plate 12, is a conductor 60.

55 One end of coil *a* of magnet 46 is grounded, the other end of said coil being connected to coil *b* of said magnet and the opposite end of this last mentioned coil is connected to lower bracket 11 by means of conductor 61.

60 The secondary circuit for the secondary clocks 62 includes a conductor 63 leading from the yoke of magnet 46 to the first one of the series of secondary clocks, and leading from the last one of said series to lower 65 bracket 11 is a conductor 64.

The operation of my improved clock is as follows:

With the parts in the positions seen in Fig. 1, it will be noted that shaft 23 is being rotated under the influence of weights carried by arms 34 and 38 and through the medium of pawls 37 and 41 which are in engagement with the teeth of ratchet wheel 31. When arm 38 has descended to the position illustrated by dotted lines *a*, Fig. 1, finger 70 75 40 will make contact with pin 50, thereby closing the primary circuit and as a result, armature 47 will be attracted by magnet 46. As said armature is attracted pin 50 will bear downward on the outer end of finger 40 80 with the result that weighted arm will be started in its upward swinging movement.

It will be understood that one of the laws of magnetism in the attraction of an armature by a magnet, is that the power decreases inversely as the square of the distance between the armature and the magnet increases. This being the case, the attraction of the armature is weakest when the current is first cut in or when the magnet 85 90 is first energized. Thus, it will be seen that when the circuit is closed and the magnet is first energized, pin 50, which is closer to the pivot point of arm 49 than pin 51, is bearing on the outer end of finger 40, said pin 50 95 constituting a fulcrum with arm 49 a comparatively short lever and finger 40 a comparatively long lever. This arrangement has the effect of making the magnet relatively more powerful during its weakest 100 105 period or at the time when said magnet is first energized, and immediately after the weighted arm has been started in its upward movement due to the downward movement of arm 49, the armature 47 has approached the magnet close enough to become more powerful with the result that the increased motion imparted to weight 39 carries said weight upward to a point where arm 38 is in substantially a horizontal plane at which 110 time the fulcrum or bearing between arm 49 and finger 40 is transferred from pin 50 to pin 51.

Inasmuch as armature 47 is now comparatively close to magnet 46 and the attraction 115 on said armature is increasing, the fulcrum or bearing point can thus be shifted from pin 50 to 51 advantageously in order to obtain the effects of the increased power or pull of magnet and during the final portion 120 of the upward movement of weighted arm 38, arm 49 performs the functions of a comparatively long lever while finger 40 is serving as a comparatively short lever.

Necessarily the arm 49 reaches its downward limit of movement when the armature 47 contacts with the core of the magnet. This downward movement of arm 49 is comparatively quick, and following the contact or bearing of the pins 50 and 51 with 125 130

the finger 40 the weighted arm 38 will be swung upward with a quick movement thereby producing momentum which causes said arm to swing upward until the weight 5 39 strikes against pad 44. In other words, the quick downward movement of the arm 49 "kicks" the weighted arm 38 upward with a quick movement and the momentum thus created necessarily swings said arm upwardly to its limit of movement and immediately after the finger 40 passes a substantially horizontal plane on its downward movement, it will leave and break contact with pin 51, thereby opening the circuit 10 through magnet 46. At this period of the operation, arm 49 is at its downward limit of movement but it is immediately swung upward under the influence of spring 48. At the time arm 49 reaches its downward 15 limit of movement, finger 36 of weighted arm 34 has not yet reached a point where it can contact with pin 51, consequently, the circuit will not be reestablished until weighted arm 34 moves downward into the 20 position shown by dotted lines in Fig. 1 and at which time the finger 36 will make contact with pin 50 thereby closing the circuit, with the result that arm 49 will be drawn down quickly and weighted arm 34 25 will be "kicked" upwardly.

A further advantage gained by the use of shifting fulcrums or contact points between arm 49 and the fingers of the weighted levers is the fact that both pins 50 and 51 30 have rubbing contact with the fingers 36 and 40 and consequently the contacting surfaces are maintained comparatively bright and clean.

Pin 50 makes contact to close the circuit 40 and pin 51 is in contact at the time the circuit is open or broken. As a result there is always a bright or clean contact at the closing of the circuit and the spark which usually occurs at the opening point or on 45 pin 51 is eliminated due to the fact that it has rubbing contact with the fingers and is therefore kept bright and clean.

As weighted arm 38 is thus swung upward, its movement will be arrested by yielding stop 42 and the impact will be broken by cushion 44.

The point of pawl 41 will reengage with one of the teeth of ratchet wheel 31, but during this upward movement of arm 38, the 55 movement of shaft 23 will in no wise be affected for the reason that said shaft is under the influence of weighted arm 34. When arm 49 reaches its downward limit of movement, or with armature 47 in contact with 60 the core of magnet 46, weighted arm 34 has not moved far enough to bring finger 36 into position where it can be engaged by either one of pins 50 and 51. As soon as weighted arm 38 has been swung upward and contact 65 is broken between pin 51 and finger 40 the

circuit through magnet 46 is broken and as a result arm 49 will swing upward under the influence of spring 48 and the upward movement of said arm will be arrested by stop cushion 53, and said arm will remain in 70 this position until weighted arm 34 has moved downward a sufficient distance to cause finger 36 to make contact with pin 50, thereby closing the circuit and repeating the operations heretofore described. Thus, the 75 weighted arms 34 and 38 are alternately actuated with the result that the shaft 23 is constantly rotated and such rotary motion is transmitted through pinions 28 to the minute and hour hands carried by shaft 26. 80

When pin 50 makes contact with either arm 36 or 40 the closed circuit includes battery 54, conductor 55, binding post 56, conductor 57, upper bracket 11, and from thence through clock frame 12, thence through 85 shaft 23, and the arm 34 or 38, which is about to make contact with pin 50, thence to said pin 50, arm 49, thence through magnet 46, through conductor 61 to lower bracket 11 which is insulated from the clock frame work 90 and from said bracket through conductor 60, binding post 58 and conductor 59, back to battery.

The secondary circuit includes battery 54, conductor 55, binding post 56, conductor 57, 95 upper bracket 11, rear plate 12, shaft 23 and either arm 34 or 38, contact pin 50, magnet 46, conductor 63, secondary clock 62, conductor 64, lower bracket 11, conductor 60, binding post 58, and conductor 59, back to 100 battery.

Necessarily, the opening of the circuit in which the master clock is located opens the circuit in which the secondary clocks are located. 105

My improved clock is arranged to close circuit and effect the winding operation at regular minute intervals, and thus said clock is especially adapted for use as the master clock in series with a number of secondary 110 clocks.

A clock of my improved construction is comparatively simple, comprises a minimum number of parts, can be easily assembled or taken apart, and by my improved system of 115 wiring, there are no electrical connections to be removed or disconnected when the clock mechanism is oiled or repaired.

It will be readily understood that minor changes in the size, form and construction of 120 the various parts of my improved clock can be made and substituted for those herein shown and described, without departing from the spirit of my invention, the scope of which is set forth in the appended claim. 125

I claim:

In an electric clock, a clock frame including a pair of connected plates, a pair of brackets supporting said plates, one of said brackets being insulated from the plate to 130

which it is connected, a pair of electro-magnet coils, one end of one of said coils being grounded on the magnet core, the end of the other coil being connected to the insulated bracket, a battery and connections therefor from said battery to the brackets.

In testimony whereof I hereunto affix my

signature in the presence of two witnesses, this 10th day of December, 1915.

ULYSSES L. COLLINS.
